[57] CLAIM

The ornamental design of a potato chip rack, as shown and described.

DESCRIPTION

FIG. 1 is a perspective of a potato chip rack showing my new design;

FIG. 2 is a side elevational view thereof;

FIG. 3 is an elevational view from the opposite side of FIG. 2;

FIG. 4 is a top plan view thereof;

FIG. 5 is a bottom plan view thereof;

FIG. 6 is an end elevational view thereof;

FIG. 7 is an elevational view from the opposite end of FIG. 6;

FIG. 8 is a perspective view of a second embodiment of that shown in FIG. 1;

FIG. 9 is a side elevational view thereof;

FIG. 10 is an elevational view from the opposite side of FIG. 9;

FIG. 11 is a top plan view thereof;

FIG. 12 is a bottom plan view thereof;

FIG. 13 is an end elevational view thereof;

FIG. 14 is an elevational view from the opposite end of FIG. 13;

FIG. 15 is a perspective view of a third embodiment of that shown in FIG. 1;

FIG. 16 is a side elevational view thereof;

FIG. 17 is an elevational view from the opposite side of FIG. 16;

FIG. 18 is a top plan view thereof;

FIG. 19 is a bottom plan view thereof;

FIG. 20 is an end elevational view thereof; and,

FIG. 21 is an elevational view from the opposite end of FIG. 20.
